UNITED STATES PATENT OFFICE.

ISIDOR KITSEE, OF CINCINNATI, OHIO.

FIRE-ANNIHILATOR.

SPECIFICATION forming part of Letters Patent No. 254,026, dated February 21, 1882.

Application filed November 25, 1881. (No model.)

To all whom it may concern:

Be it known that I, ISIDOR KITSEE, a citizen of the United States, residing at Cincinnati, in the county of Hamilton and State of Ohio, 5 have invented a new and useful Improvement in Fire-Annihilators, of which the following is a specification.

My invention relates to improvements in fire-annihilators; and it consists in devices 10 for holding in reserve magazines of simple chemicals, which are automatically discharged therefrom by the melting of fusible retaining compositions into a common receptacle, and which therein commingle and form a fire-extinguishing vapor or gas.

I have found by experience that the gases 15 or vapors in general use, when kept prepared for use for any length of time in a completed condition, become liable to deteriorate and lose their essential qualities, and that by keeping the several constituent chemicals that, when combined, compose such gases or vapors separately in their respective normal conditions, and then causing them to commingle when required for use, the gases or vapors evolved are 20 more effective for the purpose designed.

The object of my invention is to obviate the 25 objection herein pointed out of keeping fire-extinguishing vapors or gases always prepared in a completed condition; and in order to carry out my invention I employ suitable mechanical devices, which, when brought into action, empty several constituents of fire-extinguishing vapors or gases into a common reservoir, 30 where they combine and by affinity therein compose required vapors or gases, the several chemicals being retained intact in vessels held suspended over the common reservoir with their mouths downward, the mouths being 35 sealed by a fusible composition, which, being fused by the action of heat, causes the contents of the vessels to be discharged by the force of gravity into the common reservoir.

I do not herein claim broadly the retention of 40 gas and vapor producing chemicals in separate places of deposit and their ejection into a generator by melting of the retaining fusible composition, as that is embraced in another application which I have made for Letters Patent.

50 My present application relates to certain op-

erative devices, as herein described, for carrying into practice the production of the gases and vapors in the manner and for the purpose set forth.

In the drawings that accompany this specification, Figure 1 represents two vessels sealed and held suspended over a receiving-generator. Fig. 2 represents a modification of my invention.

A A' are vessels of any suitable material 60 suspended by bands e, which rest upon a base, E', though I do not confine myself to any particular mechanism for holding these vessels in position, as it is obvious that there are many devices which will perform this function without departing from the scope of my invention.

B B' are the mouths of the vessels, which have interior ribbed surfaces, d d', and flanges a' a', on which rest the stoppers a a. These stoppers are somewhat smaller in diameter 70 than the mouths of the vessels, so that when released they will easily drop out. In each of these vessels is placed a given quantity of the required chemical or chemicals. The stopper a is then inserted in position, resting upon the 75 flanges a', and the mouth of the vessel is then filled up with fusible composition f, which is firmly held in position by the ribbed edges d d'.

C is the receiver, which should contain a 80 chemical reagent from which the fire-extinguishing gas or vapor is to be generated, and which rests upon the support E. When the fusible composition is melted by the action of heat the stoppers a a fall out, releasing the chemicals, which fall into the receiver C, where 85 the gas or vapor is generated and discharged into the room.

Fig. 2 is a modification of my invention, showing a form of vessel which may be used 90 as a substitute for the vessels A A', as shown in Fig. 1. The mouth B of the vessel A² is fitted with a cap, B², which is sealed to the vessel by the fusible sealing composition f. When the composition is fused by the action of 95 the heat the cap falls off and releases the chemical contents, as in Fig. 1.

Having now fully described my invention, what I claim is—

1. In an automatic fire-annihilator, inverted vessels sealed with a fusible composition and 100

supplied with chemicals, which, when united, form a fire-extinguishing gas or vapor, and a generating-reservoir to receive the contents of said vessels, substantially as described.

5 2. In an automatic fire-annihilator, the combination of the vessels A A', having mouths B B', provided with serrated interior surfaces,

d d', and flanges a' a', with stoppers a a, sealed with fusible composition, and a receiver, C, substantially as described.

ISIDOR KITSEE.
